ICE TRAY

James H. Miner, Meridian, Miss.

Application June 22, 1936, Serial No. 86,840

2 Claims. (Cl. 62—106.5)

This invention relates to ice trays of the type used in domestic refrigeration. More particularly, the invention concerns the provision of an ice tray and removable grid which facilitates removal of the individual ice cubes.

The removal of ice cubes from the ordinary grid and tray is attendant with much annoyance as it can be effected only with difficulty. Not only is difficulty had in removing the frozen ice from the tray, but trouble is especially experienced in removing the ice from the walls forming the grid. An object of the present invention is to facilitate the removal of the ice both from the tray and from the grid.

A preferred embodiment of the invention is disclosed in the accompanying drawing, in which:

Figure 1 is a side view of the grid removed from the tray.

Figure 2 is a side view of the grid in position within a tray, on the line 2—2 of Fig. 3.

Figure 3 is a plan view of Figure 2.

Figure 4 is a section on the line 4—4 of Figure 3.

Figure 5 is a view on the right end of Figure 3.

The grid includes a carrier member 6 and a plurality of partitions 7, 8 supported thereby. The carrier member 6 is of spring material and normally assumes the curved shape shown in Fig. 1. This member 6 should be so strong that it will not be permanently distorted from ordinary use in removing the ice and should be sufficiently yieldable to be manually bent into a straight shape as shown in Fig. 2.

The partitions 7 are disposed transversely of the length of the carrier member 6 and preferably extend beyond the sides of the member 6. These transverse partitions are attached at their tops to the carrier member by rivets 9. The partitions 8 are disposed longitudinally of the carrier member and except for the endmost partition 8' are attached at one vertical side to the transverse partitions, centrally thereof. The partition 8' is separately connected at one side thereof. It should be noted that the tops of the longitudinal partitions are unattached to the carrier member and that the vertical sides of the longitudinal partitions opposite from the attached vertical sides are unattached to the adjacent transverse partition although in close relation thereto. A transverse partition and its connected longitudinal partition form a connected pair independent of the other connected pairs of partitions. As a result of this construction the carrier member is substantially as free to flex through-

out its length as though the partitions 7 and 8 were not present.

The endmost longitudinal partitions lie inwardly of the extreme ends of the carrier member 6. One projecting end of the carrier member 5 is preferably longer to form a handle or finger receiving portion 11. A depression 12 is formed across the carrier member inwardly of the portion 11 thereof.

The tray 10 is of a size to receive the grid 10 when the grid is straightened. The outer ends of the longitudinal and transverse partitions should preferably closely fit the sides of the tray so that the ice will be substantially completely subdivided. Preferably the tray is of less height 15 than the height of the partitions 7, 8 so that the carrier member 6 is held above the ice. The ice cannot, consequently, become frozen to the carrier member and the free flexing of the carrier member is not interfered with.

To retain the grid in its straightened shape within the tray, the tray is provided at one end with an overhanging hook 13 and at the other end with a movable catch 14. The hook 13 may preferably be an upwardly projecting and inwardly turned portion at the central part of the end wall of the tray. As shown in Fig. 2 this hook should not overhang the ice, in order that the ice may be removed upwardly. The catch 14 has a pinned connection at its lower end with a lug 15 formed on the tray, and has an opening 20 at its upper portion to receive the handle 11 of the carrier member.

In placing the grid within the tray the carrier member is placed with its proper end underneath the hook 13 and the grid is then straightened out within the tray by pressing downwardly upon the handle portion 11. The catch 14 is then turned into place over the handle 11 so as to be caught in the depression 12 which retains it in place. It will be noted that the handle portion 11 of the carrier member is downwardly curved 35 so that the catch 14 may be turned thereover with greater ease. Obviously, the tray may be filled with water either before or after the grid 40 is placed in position in the tray. The grid and tray when filled with water are placed in a freezing compartment in the usual manner.

To obtain the frozen cubes, the catch 14 is moved off the carrier member and the handle 50 portion 11 is then forced upwardly away from the tray. The ice cubes and grid form a united body which is moved upwardly as a unit, the ice being broken from the tray in this upward movement. It should be observed that the end wall of the 55

tray at the handle end of the carrier member is inclined outwardly to such an extent that neither the endmost longitudinal partition nor the endmost cubes will bind against this end wall in their upward movement. After removal of the grid and ice in this manner from the tray the carrier member is flexed to assume the position shown in Fig. 1. As this opens the spaces between the transverse partitions it is apparent that the ice cubes may be readily obtained. The tendency of the carrier member to spring into the shape shown in Fig. 1 materially assists the manual flexing of the grid to this shape. It will be apparent that little effort is required to obtain the ice cubes.

Instead of securing the partitions or fins by rivets, I may attach the partitions to the spring plate 8 by welding at the points substantially where the rivets occur, or in any other suitable manner, so that the flexing of the plate 8 can take place without hindrance by the fins or partitions.

After the tray is removed from the refrigerator, the catch 14 may be released and the

room temperature will cause the ice to melt slightly, but to a sufficient degree to allow the resiliency of the grid to exert itself, and the grid will creep and thereby detach itself, together with the ice cubes, from the tray.

What is claimed is:

1. An ice tray grid comprising an elongated strip-like carrier member normally longitudinally curved, said carrier member being of spring material so that it may be straightened, a plurality of partitions affixed to the convex side of the carrier member and disposed transversely thereof, and a plurality of partitions affixed each to one of the transverse partitions but free of the carrier member and other transverse partitions so as not to interfere with the free flexing of the carrier member.

2. An ice tray grid according to claim 1 in which the longitudinal partitions are each of a size to closely fit one of the spaces between adjacent transverse partitions when the carrier member is straightened.

JAMES H. MINER.
